OIL BURNER

Filed June 11, 1937

UNITED STATES PATENT OFFICE

2,172,772

OIL BURNER

August H. Pape, Kentfield, Calif.

Application June 11, 1937, Serial No. 147,717

11 Claims. (Cl. 158—91)

This invention relates to and has for an object the provision of a small, compact and inexpensive oil burner so constructed and relatively arranged as to provide for a most efficient burner operation under low heat adjustments as well as high heat adjustments, and with a low grade fuel such as Diesel oil.

Another object of this invention is to provide an oil burner of the character described, which will provide for a nicety of regulation of heat generated thereby, produce little or no smoke and operate in a comparatively economical manner with low grade fuels.

A further object is to provide an oil burner of the character described, which includes novel means for uniformly feeding fuel to the ignition chamber thereof, without waste and under minute control over a wide range of adjustments.

An additional object is to provide an oil burner of the character described, which includes a novel means for regulating the entrance of air into the burner whereby to more effectively control the operation of the burner.

I have shown in the accompanying drawing a preferred form of an oil burner embodying my invention, subject, however, to modification, within the scope of the appended claims, without departing from the spirit of my invention.

Referring to the drawing:

Fig. 1 is a section of the burner of this invention, taken on the plane of line 1—1 of Fig. 2, with certain parts broken away for the sake of clarity of illustration.

Fig. 2 is a sectional view taken on the plane of line 2—2 of Fig. 1, and

Fig. 3 is a cross sectional view taken on the plane of line 3—3 of Fig. 1.

One embodiment of the oil burner of this invention, as shown in the accompanying drawing, comprises a burner housing consisting of upper and lower sections 4 and 5 held together by means of screws 6 and forming a substantially rectangular enclosure open at both ends. The bottom wall of the lower section 5 is extended in the form of a bowl or pan 7, having an upwardly and outwardly inclined arcuate side wall 8 and being of substantially duck-bill shape, for directing the flames forwardly and upwardly therefrom.

Removably mounted within the housing is a substantially rectangular ignition chamber 9 open at both ends and adapted to have oil supplied thereto from oil feed means 10. As here shown, the means 10 comprises a feed pipe 11 connected with a source of supply of oil, not

shown, and which discharges past a control valve 12 into a fitting 13 supporting a feed wire 14. The fitting 13 has a bore 15 in greater diameter than that of the wire and which communicates with the pipe 11 through a passage 16. However the upper portion of the fitting 13 is in close frictional engagement with the wire so that the latter may be adjusted vertically in the fitting and will remain in position of adjustment. The wires are provided with a lateral handle portion 17. Fuel discharging into the bore 15 will gravitate on the wire 14 into the burner, there being an opening 18 in the upper side of the housing through which said wire extends and a similar opening 19 in the upper wall of the ignition chamber 9. As shown in Fig. 2, the lower end of the wire 14 engages in a centering depression 20 formed in a fuel cup 21 provided within the ignition chamber. Beneath the cup 21 is a similar but larger cup 22 which is adapted to catch the overflow of fuel from cup 21. Unlike cup 21 which is closed at one end and open at the other to prevent an air draft through it, the cup 22 is open at both ends to permit the atmospheric air to pass between said cups and commingle with fuel and vapors discharging from the open end of cup 21 in the operation of the burner. Beneath the cup 21 is an air passage 23 extending the full length of the ignition chamber and it will be noted that the inner or discharge end of said chamber is restricted by turning up the end 24 of the bottom wall thereof. The housing 4 is provided at the inner end thereof with spaced flanges or baffles 25 and 26.

The passage of air between the housing and ignition chamber to support combustion at the outlet end of said chamber is regulated by means of plate valves 27 and 28 pivoted as at 29 to the housing close to opposite sides of the ignition chamber. The free ends of the valves are adapted to be moved into and out of engagement with the side walls of the housing. It is noted that the ignition chamber is fitted within the housing so that air passages are provided on opposite sides thereof only, and the valves 27 and 28 act as dampers for controlling the flow of air through said passages. These valves may be adjusted by means of a lever 30 connected by links 31 and 32 with the valves and operated by means of a pivoted handle 33, one end of which is extended out of the housing. In Fig. 1 the valves 27 and 28 are shown in full lines as when closed and in dotted lines as when open.

The top wall of the upper section 4 of the housing is inwardly offset as at 34, so as to con-

tact the upper wall of the ignition chamber as shown in Fig. 2, whereas the remainder of said upper wall is spaced from the ignition chamber to accommodate the means for operating the valves 21 and 28. The bottom floor wall of said ignition chamber rests on the corresponding wall of the lower section 5. The lower section 5 is provided with an upstanding flange 35 at the intake end of the housing, to prevent the chamber 9 from sliding out of the housing and also retain liquid fuel in said section. It will be seen that the chamber 9 may be readily lifted above this flange for removal thereof and similarly lifted when inserted in place within the housing.

In the operation of the burner of this invention, the valve 12 is open as desired, and the fuel will run through the passage 16 into the bore 15 and gravitate down the wire 14 into the cup 21. If desired, this wire may be vertically adjusted sufficiently to visually determine the rate of flow as shown in Fig. 3. Furthermore, this member is lifted in this manner when placing or removing the ignition chamber. A suitable wick, not shown, saturated with fuel, is placed in the cup 22 and ignited to start the burner. As soon as the burner becomes heated the fuel therein will gasify and flame, as indicated in Fig. 2, will be directed forwardly and upwardly from the burner. The ignition or burning of the fuel takes place substantially at the forward edges of the cups 21 and 22. The closing of the outer end of cup 21 prevents an air draft over the top thereof and said cup will therefor give off a rich fuel vapor at the open end thereof when heated by the flame from said wick or otherwise.

It will be seen that the air to support combustion will pass through the space 23 in the ignition chamber and also through the space between the cups 21 and 22, and if the valves 21 and 28 are open, the two air passages on opposite sides of said ignition chamber will conduct atmospheric air to a point adjacent to the discharge end of the ignition chamber. This incoming air is deflected by the flanges 25 and 26. It will be noted that the discharge end of the ignition chamber is spaced slightly inwardly from the discharging end of the housing to accommodate the introduction of atmospheric air at such points. Upon closing these valves 21 and 28, atmospheric air enters the burner through the ignition chamber passages only. It will thus be seen that valves 21 and 28 provide for regulation of the burner under a low or intense heat over a wide range of adjustment. By adjusting the valve 12 the burner may be further regulated as to the amount of fuel fed thereto and also the intensity of the heat generated thereby. It is important to note that the bore 15 being of a predetermined size relative to the diameter of the wire 14 will cause a predetermined amount of fuel to flow at a more or less given rate into the burner, so that no overflow or waste of the fuel will take place and only that amount necessary to produce a flame of predetermined maximum intensity will be fed to the burner, regardless of adjustment of the valve 12.

It is important to note that the particular method of feeding fuel in accordance with this invention, and the especially constructed ignition chamber provide for thorough combustion of low grade fuel with a minimum of smoke, while adjusted for low heat as well as high heat, and throughout the entire range of adjustment between the limits thereof. It should also be noted that the valves 21 and 28 will act as a centering

means for the ignition chamber relative to the housing, this centering being also contributing by the screws or fastenings 6 between which, said chamber extends.

The burner parts are constructed of comparatively heavy metal and are connected so that the heat generated by the burner will be more effected for gasifying the fuel. The burner of this invention is subject to ready installation in stoves, furnaces, and is otherwise applicable to all uses of oil burners in a particularly efficacious manner, the efficiency of the burner being aided by the draft created by the equipment in which it is used and the construction of the burner renders this draft effective to introduce atmospheric air and cause gasification of the fuel without the aid of blowers, pressure means, or fuel atomizing means of any kind whatsoever.

The lower wall of the ignition chamber 9 is also upturned as at 24', so that said wall constitutes in effect a third cup. With this arrangement the chamber consists of a plurality of superposed spaced cups affording between the lowermost thereof, air passages, each cup being longer than the other from the upper to the lower end thereof.

It should be noted that the draft of air passing through the chamber 9 will cause fuel vapors to be drawn from the cups 21, 22, and also from the bottom wall of the chamber. Should this draft be excessive it may be reduced by opening the valves 21 and 28 and allowing some of the air to pass between the sides of the chamber and housing. Thus it is seen that the valves 21 and 28 will provide for an effective adjustment of the burner to cause it to operate in the desired manner in various installations and particularly under low heat adjustments although high heats may also be produced. The fuel cup 21 in being closed at one end prevents air from flowing over the top of the cup. Thus the vapors given off at the open end of the cup are comparatively rich and become admixed with air passing between cups 21 and 22.

I claim:

1. An oil burner comprising a housing open at its ends, an ignition chamber open at both ends and mounted within the housing and defining a passage for atmospheric air between it and said housing, a valve means for controlling the flow of air through said passage and means for introducing fuel into said chamber.

2. An oil burner comprising a housing open at its ends, an ignition chamber open at both ends and mounted within and defining between it and said housing a passage for atmospheric air, superposed fuel cups mounted within said ignition chamber and arranged so as to successively overflow one into the other from the uppermost to the lowermost thereof, means for introducing fuel into the uppermost cup, and valve means for controlling the flow of air through said passage.

3. An oil burner comprising a housing open at its ends, an ignition chamber within the housing, spaced therefrom to define a passage for atmospheric air through said housing and being open at both ends, a fuel cup mounted within said ignition chamber, means for introducing fuel into said cup, including a wire extending into said cup, and means for feeding fuel onto said wire.

4. An oil burner comprising a housing open at both ends, an ignition chamber removably mounted within and defining between it and the

housing passages for atmospheric air, valves for controlling the passage of air through said passages, said ignition chamber being open at both ends and having one end spaced inwardly from an end of said housing, and means for introducing fuel into said ignition chamber.

5. An oil burner comprising a housing open at both ends, an ignition chamber removably mounted within and engaged with said housing

10 to define therebetween passages for atmospheric air, valves for controlling the passage of air through said passages, said ignition chamber being open at both ends for the passage of air therethrough and the discharge of products of combustion and fuel vapors therefrom, and means for introducing fuel into said combustion chamber, said housing having the lower wall thereof extended in the form of a bowl to deflect products of combustion upwardly from one open end thereof.

20 6. An oil burner comprising a housing open at both ends, an ignition chamber mounted within and engaged with said housing to define therebetween a passage for atmospheric air, valve means for controlling the passage of air through said passage, said ignition chamber being open at both ends, a fuel cup in said chamber, and means for introducing fuel into said cup, said cup being closed on one side to prevent the passage

30 of air over the upper side thereof and being open on its opposite side to permit discharge of fuel.

7. An oil burner comprising elongated housing open at both ends for the passage of atmospheric air therethrough, an elongated ignition chamber open at both ends and mounted within said housing and spaced therefrom to define air passages therebetween, valve means for controlling said air passages, means for operating said valves including a lever extending outwardly from one end of the housing, a fuel cup provided internally of said chamber adjacent the air intake end of the latter, a closure for that portion of the intake end of the housing which lies above said cup, said housing having an opening therein and a fuel feed wire extended through said opening into said cup, and means for depositing fuel on said wire including a valve controlling the feed of fuel to said wire.

8. In an oil burner, a housing open at both ends, an ignition chamber open at both ends and mounted within said housing so as to define air passages between it and said housing, a plural-

ity of fuel cups spaced one above the other in said chamber, means partially closing one end of said chamber to prevent the passage of air over the open side of the uppermost cup, valve means within said passages for controlling the passage of air therethrough, and means for feeding fuel into the uppermost cup.

9. In an oil burner, a housing open at both ends, an ignition chamber open at both ends and mounted within said housing so as to define air passages between it and said housing, a plurality of fuel cups spaced one above the other in said chamber, means partially closing one end of said chamber to prevent the passage of air over the open side of the uppermost cup, valve means disposed within and between the ends of said housing for controlling the flow of air through said passages, and means for feeding fuel into the uppermost cup, each cup having one end extended outwardly beyond the end of the cup above it.

10. An oil burner comprising an elongated housing open at its ends, an elongated ignition chamber open at both ends and mounted in said chamber with certain walls in contact with walls of the housing opposite thereto and other walls spaced from the housing walls opposite thereto to define air passages, valves operable in and for controlling said passages, said chamber having one end spaced inwardly from an adjacent end of the housing, flanges on said housing for directing the air from said passages towards said end of said chamber, and means for introducing liquid fuel into said chamber.

11. An oil burner comprising an elongated housing open at its ends, an elongated ignition chamber open at both ends and mounted in said chamber with certain walls in contact with walls of the housing opposite thereto and other walls spaced from the housing walls opposite thereto to define air passages, valves operable in and for controlling said passages, said chamber having one end spaced inwardly from an adjacent end of the housing, flanges on said housing for directing the air from said passages towards said end of said chamber, and means for introducing liquid fuel into said chamber, a fuel cup in said chamber below the plane of the upper wall thereof for receiving fuel from said feed means, and means closing that portion of one end of said chamber which lies above the plane of the cup.

AUGUST H. PAPE.
